UNITED STATES PATENT OFFICE.

FRANK W. WALLACE, OF CHATTANOOGA, TENNESSEE, ASSIGNOR OF ONE-HALF TO
ALBERT E. DOYLE, OF CHATTANOOGA, TENNESSEE.

DENTAL IMPRESSION-TRAY.

1,378,297.

Specification of Letters Patent. Patented May 17, 1921.

Application filed January 20, 1921. Serial No. 438,734.

To all whom it may concern:

Be it known that I, FRANK W. WALLACE, a citizen of the United States, residing at Chattanooga, in the county of Hamilton and

5 State of Tennessee, have invented certain new and useful Improvements in Dental Impression-Trays; and I do declare the following to be a full, clear, and exact description of the invention, such as will enable others skilled in the art to which it ap- 10 pertains to make and use the same.

My invention relates to improvements in dental impression trays and more particularly to a device of this character intended 15 for the purpose of taking impressions for the more modern practice of "removable bridgework." This requires a perfect impression with a minimum of fracture of the impression material, and my invention aims 20 to fulfil this requirement by providing a dental impression tray having an upstanding fin which partially splits the impression material and thereby insures accurate cleaving.

25 With the foregoing in view, the invention resides in the novel construction and arrangement hereinafter described and claimed, the descriptive matter being supplementd by the accompanying drawings.

30 Figure 1 is a top plan view showing one form of a dental impression tray constructed in accordance with my invention.

35 Figs. 2 and 3 are respectively longitudinal and transverse sectional views as indicated by the lines 2—2 and 3—3 of Fig. 1.

Figs. 4, 5 and 6 are duplicates of Figs. 1, 2 and 3 with the exception that they show a slightly different form of construction.

40 In the drawings above briefly described, the numeral 1 designates a curved channel-shaped impression tray preferably having a loop 2 on its bottom for the attachment of a removable handle. Secured either temporarily or permanently to the bottom 3 of 45 the tray 1 and extending throughout the length of said bottom, substantially along its center, is an upstanding relatively narrow flange or fin 4 which is provided on its upper edge with an integral upstanding lug 5 as seen in Figs. 1, 2 and 3, or with a plurality of such lugs as indicated at 6 in the other figures, the lug or lugs being of slightly less height than the side walls 7 of the

tray 1 so as to cut almost entirely through the impression material when it is placed 55 in the tray, thereby insuring proper cleavage of the impression material after taking the impression. The form of construction shown in Figs. 1, 2 and 3 is intended for taking impressions of a number of teeth 60 while the other form of the invention is designed for taking an impression of a single tooth. The action of the device is the same in both cases and it will insure the unusually accurate impressions which are 65 necessary in connection with removable bridgework.

From the foregoing, taken in connection with the accompanying drawing, it will be seen that although my invention is of extremely simple and inexpensive nature, it will be highly efficient and in every way desirable, and since probably the best results may be obtained from the details disclosed, such details may be followed if desired. I 70 wish it understood however that within the scope of the invention as claimed, numerous minor changes may well be made. Furthermore, any desirable or suitable materials may be used in the manufacture of the 75 device, and as before stated the fin or the like 4 may be either permanently or temporarily secured in the tray.

I claim:

1. A dental impression tray having an up- 85 standing flange provided on its upper edge with a vertical lug in the same plane with said flange and of slightly less height than the side walls of the tray.

2. A dental impression cup comprising a 90 curved channel-shaped tray, a relatively narrow flange rising from the central portion of said tray and extending substantially throughout the length thereof, and a vertical lug rising from the upper edge of 95 said flange and located in the same plane with said flange, said lug being of slightly less height than the walls of the tray.

3. A dental impression tray having a flat 100 upstanding lug rising from its bottom and of only slightly less height than the side walls of the tray.

In testimony whereof I have hereunto set my hand.

FRANK W. WALLACE.
